SHOE HOLDER AND CLAMP FOR POLISHING PURPOSES

Johnde W. Brewer, Des Moines, Iowa

Application December 19, 1947, Serial No. 792,778

4 Claims. (Cl. 15—267)

1

This invention relates to an improved shoe holder particularly adapted for domestic use.

It is the object of my invention to provide a device of simple, durable and inexpensive construction for holding shoes or boots while being polished and cleaned and especially adapted for household use, which may be easily supported from a wall or other support in a quick and detachable manner.

A further object of my invention is to provide a shoe holder having improved means for adjustably clamping the shoe firmly in operative position.

My invention consists in the construction, arrangement and combination of the various parts of the device whereby the objects contemplated and attained as hereinafter more fully set forth, pointed out in my claims and illustrated in the accompanying drawings, in which:

Figure 1 is a side elevation of my improved shoe holder, showing the manner that it is mounted on a wall or other support.

Figure 2 is a top plan view of Figure 1.

Figure 3 is a detail sectional view taken on the line 3—3 of Figure 1.

Figure 4 is a sectional view taken on the line 4—4 of Figure 1.

Figure 5 is a sectional view taken on the line 5—5 of Figure 1.

Figure 6 is a detail sectional view taken on the line 6—6 of Figure 1.

My improved shoe holder comprises a wall cleat 10 secured to a wall 11 or other suitable support by screws 12. The upper end of the cleat is wider than its lower end and has its edges provided with inturned flanges 13, for detachably receiving the tapered supporting bar 14 of the shoe supporting frame 16. Said frame comprises the bar 14, a horizontal portion 17 and a brace portion 18 having the lower end provided with notches 19 to permit the tapered plate 14 to be moved upwardly from the flanges 13, whereby the frame 16 may be easily and quickly attached to or detached from the wall bracket.

The upper end of the brace 18 is provided with a horizontal portion 21 having an opening 22. A bar 23 is mounted under the frame member 17 and adapted to slide longitudinally between the portions 17 and 21. Said bar is provided with a hook 24 at its outer end and a slot 26 in its opposite end. A clamp 27 having a bottom portion 28, side member 29 and an opening 31, is provided for clamping the parts 21, 23 and 17 firmly together. A bolt 32 and a thumb nut 30 are pro-

2

vided for securing the clamp and said parts together.

Pivottally mounted to the member 17, I have provided a heel plate 34 having upwardly projecting heel engaging lugs 36.

In the practical operation of my improved shoe holder, assuming that the wall bracket has been secured to the wall 11 or any other convenient support, the frame 16 is then grasped and the plate 14 of said frame placed in the bracket 10 between the front face of said wall cleat and the flange portions 13; the notch 19 permitting the lower end of the brace 18 to enter between the lower ends of the flanges 13. This provides means for rigidly holding the frame 16 to the wall. The thumb nut 30 and the clamp 27 is then loosened permitting the bar 23 to be pulled outwardly from the wall. The heel of a shoe is then placed on the plate 34 with the back of the heel engaging the lugs 36 with the ball of the shoe sole resting on the bar 23. The said bar is then moved inwardly until the hook 24 engages the toe portion of the shoe sole. The nut 32 is then tightened causing the parts 17, 23 and 21 to be firmly secured together and the shoe firmly held in position for polishing or cleaning.

The slot 26 in the bar 23 provides for moving the hook 24 toward or from the heel plate 34 to permit shoes of various lengths to be polished. By pivotally mounting the heel plate to the bar 17 by means of the rivet 38, means is further provided for adjusting the length of the supports. This is accomplished by swinging the heel plate through an angle 180° as shown in dotted lines 35 in Figure 2. The heel of the shoe will then engage the back edges 37 of the lugs 36 instead of their inner faces, thereby providing simple means for further adjusting the length of the holder to provide for very short shoes, such as that of a child.

Thus it will be seen that I have provided a shoe holder of very simple and cheap construction which may be easily and quickly applied to or removed from a support, such as a wall and when so applied provides a shoe holder capable of being adjusted to various size shoes and when so adjusted firmly hold the shoe so that it may be easily polished or cleaned.

I claim:

1. A shoe holder comprising, a wall cleat, a horizontal support detachably connected to the wall cleat, a heel plate having upwardly extending heel engaging lugs near one edge, means pivotally connecting the opposite edge of said plate to one end of said support to swing in a horizontal plane,

a toe hook adjustably mounted to the other end of said support to move toward and from said heel plate, and means for locking said toe hook in any one of its adjustable positions.

2. A shoe holder comprising, a horizontal support adapted to be secured to suitable supporting means, a toe hook secured to the outer end of said horizontal support, a heel clamp having upwardly extending lugs near one of its edges, means pivoting the opposite edge of said clamp to said horizontal support near its inner end to rotate in a horizontal plane through an angle of 180° to either of two operative positions to increase or decrease the distance between the heel lugs and said toe clamp.

3. A shoe holder comprising, a supporting frame including a horizontal portion, a downwardly extending wall engaging portion having its lower end inclined upwardly and outwardly to form a brace, a bar slidably supported between the lower face of the horizontal portion and the upper end of said brace, the outer end of said bar terminating in a toe-hook, a heel clamp pivotally secured to the inner end of said horizontal portion to rotate through an angle of 180°, and means for adjustably clamping the slideable bar to and between said horizontal portion and the brace member to permit the toe-hook to move toward and from the heel clamp.

4. A shoe holder comprising, a vertical wall cleat having spaced bracket supporting flanges inclined downwardly and inwardly, a supporting frame including a horizontal support, a vertical plate tapered and adapted to engage and fit the flanges of said cleat, and a brace member extending upwardly and outwardly from the lower end of said tapered plate with its upper end terminating in a horizontal portion slightly spaced from the under side of the outer end of said horizontal

support, a slotted bar supported between the horizontal support and the horizontal portion of said brace the outer end of the slotted bar having an upwardly extending toe-hook; a clamping plate 5 beneath the horizontal portion of said brace having upwardly projecting flanges for engaging the edges of said horizontal portion and said slotted bar, a bolt supported through said horizontal portion, the slot of the adjustable bar, the horizontal portion of said brace, and said clamp plate, a wing nut on the lower end of said bolt for clamping all of the last said parts together, a heel plate 10 having its forward edge pivotally mounted on the horizontal portion of said frame and its rear edge provided with upwardly extending heel engaging lugs; whereby the toe hook is adjustably mounted to move toward and from the heel plate to lengthen or decrease the distance between the toe-hook and the heel lugs, the heel plate being 15 pivotally mounted to rotate through an angle of 180° to further shorten the distance between said heel lugs and toe hook.
